UNITED STATES PATENT OFFICE.

EUGENE L. BROWN, JR., OF CHICAGO, ILLINOIS, ASSIGNOR TO R. E. SPENCER GEARE,
OF CHICAGO, ILLINOIS.

FEED GATE FOR AUTOMATIC STOKERS.

Application filed June 21, 1920. Serial No. 390,437.

To all whom it may concern:

Be it known that I, EUGENE L. BROWN, Jr., a citizen of the United States, residing at Chicago, in the county of Cook and State of Illinois, have invented certain new and useful Improvements in Feed Gates for Automatic Stokers, of which the following is a specification.

This invention relates to improvements in feed gates for automatic stokers and has, for its object, to provide a device of this nature which may be assembled and disassembled with a minimum of time and trouble.

In feed gates in present day use, it is customary to support the tile of the same in such wise that the burning out of the metal backing, resulting from hopper fires and the like, results in the disintegration of the feed gate with consequent necessity for shutting down the stoker with increased annoyance in repairing and replacing the same.

In my device, the refractory material comprising the protecting portion of the feed gate is suspended in such wise that the burning out of the metal backing will not effect its support so that it will ordinarily continue to function. Furthermore, should the lower portion of the refractory gate become broken or cracked, even should it become displaced, the balance of the refractory material will still remain in place and function. Also, should unusual conditions result in burning off or breaking of the lower part of the hangers the block or brick will be suspended and continue to function. Another object of my invention is to provide a structure which, when it is necessary to repair the refractory portion of the gate, such may be done without shutting down the stoker. These and other objects will be more fully set forth in the accompanying drawings in which—

Fig. 1 is a vertical longitudinal section through a portion of a furnace showing my improved feed gate;

Fig. 2 is a front elevation of the gate proper; a portion thereof being shown in section;

Fig. 3 is a perspective of one of the hangers;

Fig. 4 is a detail showing a refractory block or brick in the process of application to a hanger; and,

Fig. 5 is a plan view of one of the refractory members.

Like numerals denote like elements throughout the drawings, in which—

10 designates a front of a furnace having a guide plate 10^a located in front and on each side thereof and spaced therefrom. 11 designates the front end of the furnace arch. 12 indicates a vertically reciprocable carrier having an outwardly projecting flange 12^a provided with the slots 12^b therein (see Figs. 1 and 2). An apron 13 is secured at its lower edge by bolts 13^a or the like in a seat in the carrier 12, its sides being guided in vertical movements by the guide plates 10^a. At suitable locations along the front of carrier 12 are provided the spaced lugs 12^c, each pair of which is engaged by cross-pin 14 carried by the chain 15 engaging the sprocket 16 which is mounted upon the square shaft 17 which may be rotated to raise or lower the carrier 12.

A plurality of hangers 18 are provided, being circular in cross-section and being tapering from bottom to top, to provide a frusto-conical portion, although I do not wish to be restricted to this specific form. At the top, these hangers are each provided with a projecting ear 18^a transversely apertured at 18^b.

A refractory block 20 is provided for each of the hangers 18, these blocks being provided with a vertical bore 20^a tapering from bottom to top in substantial correspondence to the tapered hanger 18. The vertical slot 20^b leads to a face of the block from the bore 20^a, the slot being of a width slightly greater than the ear 18^a. At its upper portion, the block is recessed or notched at 20^c to accommodate a downwardly projecting portion 12^d of carrier 12 (see Figs. 1 and 4). At its lower rear corner, the block is chamfered or beveled at 20^d.

In assembling the structure described above, the hangers 18 are turned to the position shown in Fig. 4, relative to the block 20 and moved upwardly in the bore 20^a thereof, the ear 18^a sliding in the slots 20^b, as shown, until the hanger 18 is moved to the position engaging the tapered bore 20^a when it is rotated 180 degrees to the relative position shown in Fig. 1 in which position the ear 18^a extends upwardly through the slot 12^a.

Metallic cover plates 21 are provided for each of the bricks 20, these plates being provided with an angularly disposed upper

flange 21^a resting upon the flange 12^a of the carrier 12. Each cover plate is provided with a slot 21^b in the flange 21^a through which the ears 18^a may project. A trans-
5 verse tapered key 25 is driven through the aperture 18^b of each ear 18^a, its tapered construction serving to wedge the hanger cover plate and block in assembled relation with respect to the carrier 12. The cover plate
10 21 is inclined at its lower end at 21° to conform to the chamfered portion 20^d of block 20.

It will be obvious that should hopper fires occur where my feed gate is used and should such fire result in the burning off of cover plates 21, the reciprocable brick or block 20 will still be suspended from the hangers 18, thereby affording protection from the body of the fire. Furthermore, should a portion 20 of the block 20 become cracked or broken, its falling away will not result in the disengagement of the balance of the block of the hanger 18, as will be obvious.

Furthermore, should it become necessary to replace or repair any part of the feed gate during the operation of the stocker mechanism and furnace, it is possible to repair it without shutting down the stoker, merely knocking out such hanger keys 25 as may be necessary and removing the structure to be repaired, quickly and readily replacing it with a new structure.

It is obvious that my invention is susceptible of numerous modifications and improvements and I do not wish to be restricted to the form shown, except as defined in the appended claims.

What I claim is:—

1. A feed gate for furnaces comprising a carrier, a plurality of refractory members, and an individual hanger for each of said members detachably suspended from said carrier.

2. A device of the class described, comprising a carrier, a hanger attached at its upper end to said carrier and depending below the latter, a refractory member carried by said hanger, and a metal cover for said member, said cover being also carried by said carrier.

3. A device of the class described, comprising a reciprocable carrier, said carrier having an apertured flange, a hanger having a portion extending through said aperture of the flange, means to detachably secure said hanger to said flange, a refractory block carried by said hanger and depending below said carrier.

4. A device of the class described, comprising a reciprocable carrier, said carrier having an apertured flange, a hanger having a portion extending through said aperture of the flange, means to detachably secure said hanger to said flange, a refractory block carried by said hanger and depending below

said carrier, said block being provided with a tapered bore, said hanger being provided with a tapered portion seated in said bore.

5. A device of the class described, comprising a reciprocable carrier, said carrier having an apertured flange, a hanger having a portion extending through said aperture of the flange, means to detachably secure said hanger to said flange, a refractory block carried by said hanger and depending below said carrier, said block being provided with a tapered bore, said hanger being provided with a tapered portion seated in said bore, said block being further provided with a relatively narrowed slot leading from said bore, the flattened portion of said hanger being insertable through said slot.

6. A device of the class described, comprising a carrier member having an apertured projecting flange, a hanger member having a portion extending through said aperture, a metal member having a portion resting upon said flange and apertured to permit extension therethrough of said hanger portion, a key member engaging said hanger portion above said cover and flange to secure said hanger, cover, and flange in assembled relation.

7. A device of the class described, comprising a carrier member having an apertured projecting flange, a hanger member having a portion extending through said aperture, a metal member having a portion resting upon said flange and apertured to permit extension therethrough of said hanger portion, a key member engaging said hanger portion above said cover and flange to secure said hanger, cover, and flange in assembled relation, a refractory block carried by said hanger.

8. A device of the class described, comprising a carrier member having an apertured projecting flange, a hanger member having a portion extending through said aperture, a metal member having a portion resting upon said flange and apertured to permit extension therethrough of said hanger portion, a key member engaging said hanger portion above said cover and flange to secure said hanger, cover, and flange in assembled relation, a refractory block carried by said hanger, said block being provided with a tapered bore, said hanger being provided with a tapered portion seated in said bore.

9. In a feed gate for furnaces, a carrier, means for supporting the same, a plurality of hangers depending from said carrier, a refractory block supported by each of said hangers, and individual cover plates for said blocks.

10. In a feed gate for furnaces, a carrier, means for supporting the same, a plurality of hangers depending from said carrier, a refractory block supported by each of said

hangars, and individual cover plates for said blocks, said plates being also supported from said carrier.

11. In a feed gate for furnaces, an L-shaped carrier, an inverted L-shaped protector plate, corresponding flanges of said members overlapping and provided with aligned openings, a hanger engaging through said openings at its upper end and depending below said carrier, fastening means for said hanger, and a refractory block carried by said hanger below said carrier and behind said plate.

12. In a feed gate for furnaces, an L-shaped carrier, an inverted L-shaped protector plate, corresponding flanges of said members overlapping and provided with aligned openings, a hanger engaging through said openings at its upper end and depending below said carrier, fastening means for said hanger, a refractory block carried by said hanger below said carrier and behind said plate, and a depending element carried by said carrier and engaging within a cut-out portion of said block.

13. In a feed gate for furnaces, a reciprocable carrier element having a laterally projecting flange, a protector plate depending from the carrier and having a flange engaging the carrier flange, said flanges having aligned openings therein, a hanger engaging through said openings and depending from said flanges behind said plate, a refractory block carried by said hanger,

and means for fastening said hanger in position.

14. In a feed gate for furnaces, a reciprocable carrier element having a laterally projecting flange, a protector plate depending from the carrier and having a flange engaging the carrier flange, said flanges having aligned openings therein, a hanger engaging through said openings and depending from said flanges behind said plate, a refractory block carried by said hanger, and means for fastening said hanger in position, said means comprising a key engageable through an opening in the upper end of said hanger above said flanges.

15. A feed gate for furnaces, comprising a carrier having a laterally projecting apertured flange, a hanger detachably suspended from said flange, and a refractory block carried by said hanger, said hanger engaging through said aperture at its upper end and being held in position by means of a key engageable through an aperture in said hanger above said flange.

16. A feed gate for furnaces, comprising a carrier having a laterally projecting flange, a hanger detachably suspended from said flange, a refractory block carried by said hanger, and a protector plate covering one side of said block and being also detachably suspended from said carrier.

In testimony whereof, I have subscribed my name.

EUGENE L. BROWN, JR.
